UNITED STATES PATENT OFFICE.

SAMUEL ELLIOTT, OF GREENSBORO, NORTH CAROLINA, ASSIGNOR TO SHUR KLAMP MOP HOLDER CORP., OF GREENSBORO, NORTH CAROLINA, A CORPORATION OF NORTH CAROLINA.

MOP CLAMP.

Application filed February 16, 1925. Serial No. 9,666.

This invention relates to mop clamps or holders, particularly adapted for holding mop heads, mops, rags, waste and other material used for mopping floors, drying floors, 5 washing windows, automobiles and generally used in cleaning and scrubbing.

One of the primary objects of the invention is to provide a clamp which may be attached to the handle without the necessity 10 of the handle being threaded, reduced or otherwise weakened, and also avoiding the cost of producing such threads or reductions.

Another object of the invention is to provide a clamp that will permit mops of different size to be readily grasped and securely held without slipping, and also hold the mop in such a way that it may be readily detached when it becomes matted or is to 15 be replaced by a new one. In that connection, it is proposed to provide a novel clamping lever that performs the dual function of manipulating a movable clamping jaw and also places the same under compression 20 thereby to hold the clamping jaw in engagement with the mop.

With the above and other objects in view which will more readily appear as the nature of the invention is better understood, 25 the same consists in the novel construction, combination and arrangement of parts hereinafter more fully described, illustrated and claimed.

A preferred and practical embodiment of 30 the invention is shown in the accompanying drawing, in which:—

Figure 1 is a side elevation of the improved mop clamp.

Figure 2 is a top plan view thereof.

Figure 3 is a detail perspective view of the combined rigid jaw and attaching sleeve unit.

Figure 4 is a cross-sectional view taken on the line 4—4 of Figure 1.

Similar reference characters designate corresponding parts throughout the several figures of the drawings.

In the manufacture of mop clamps for the market it is necessary not only to consider the item of manufacturing cost but to 50 also consider convenience of manipulation as well as proper provision for preventing accidental disengagement of the mop from the mop clamp. Also, the clamp must be

constructed in such a way that it has no 55 awkward projections that are likely to mar or scratch floors or furniture.

Accordingly, with a view to providing a 60 mop clamp meeting the above requirements, and which is also strong, and economically manufactured, it is proposed to provide a 65 clamp unit comprising a fixed jaw 1 and an attaching sleeve 2, the said jaw 1 being provided with teeth 3 and the sleeve 2 being formed to telescopically receive the full diameter of the handle H. This combined 70 jaw and attaching sleeve unit may be formed from a single stamping of metal, and the jaw formed as shown, while the tubular sleeve portion 2 is preferably closed at its front end to strengthen or brace the sleeve 75 while the rear end is provided with the perforated ears 4. With the construction described, it will be apparent that the attaching sleeve may be readily fitted over the end of the handle H and may be secured thereto by means of the fastening 5 which passes through the openings 6—6 in the sides of the sleeve. The said fastening 5 80 may be a bolt, rivet or the like, and also serves as the pivot axis of the jaw manipulating lever designated generally as L.

The fixed jaw 1 previously referred to 85 cooperates with a movable jaw 7 which comprises a substantially T-shaped body portion having a mop clamping head 8 provided with teeth 8^a and the end of the shank portion of the body being formed 90 with the down-turned perforated ears 9 for registering with the perforated ears 4 thereby to receive a combined jaw pivot and lever anchoring pin 10. The movable clamping 95 jaw 7 is preferably made of spring metal and the intermediate portion thereof is provided with laterally projecting lugs 11—11 adapted to ride in the slots 12 in the arms 13 of the manipulating lever L.

Referring further to the manipulating 100 or compression lever L it will be observed from Figures 1 and 4 that arms 13 merge into the body portion 14 which is looped as indicated at 15, thereby to receive a substantially U-shaped bail 16 having the hooked ends 17 for engaging over the projecting ends of the anchoring pin 10.

From the foregoing description, it will be apparent that the several parts of the mop clamp may be readily stamped from sheet

metal and bent into the desired formation by simple forming operations. The attaching sleeve 2 may be readily fitted over the handle H and held in place by the insertion of the combined fastening and pivot member 5. The movable clamping jaw 7 may then readily be placed in position whereby the lugs 11 operate within the slots 12, and the combined anchoring and pivot pin 10 may 10 then be driven through the handle so that the ends thereof will readily receive the hooked portions 17 of the holder bail 16.

When it is desired to place a mop between the jaws 1 and 8, the same may be separated 15 as indicated in dotted lines to permit of the insertion of the mop. The compression lever L may then be operated to cause the edges of the slots 12 to pull down on the lugs 11, thereby closing the jaws against the mop and 20 placing the upper clamping jaw under tension, the lugs 11 riding along the slots as the end of the lever is compressed to the point where the hooked ends 17 of the bail 16 will engage over the anchor projections of the pin 10. When it is desired to release the mop 25 from the jaws of the clamp the lever L is compressed sufficiently to permit the hooked ends 17 to disengage the pin 10 and then the lever L may be manipulated thereby to release the clamping jaw 7 and also assist in 30 forcing it away to facilitate the removal of the mop.

Without further description it is thought 35 that the features and advantages of the invention will be readily apparent to those skilled in the art, and it will of course be understood that changes in the form, proportion and minor details of construction may be resorted to without departing from 40 the spirit of the invention and scope of the appended claims.

I claim:

1. A mop clamp comprising a combined fixed jaw and tubular handle attaching

sleeve, a movable clamping jaw of resilient 45 metal pivotally connected to the rear end of the attaching sleeve, laterally projecting lugs on the movable clamping jaw, a lever on said sleeve having slotted arms for receiving the said lugs, and means carried by the end of 50 said lever for holding the same toward the attaching sleeve thereby to place the clamping jaw under tension.

2. A mop clamp comprising a combined fixed jaw and a tubular handle attaching 55 sleeve, a movable clamping jaw having laterally projecting lugs, a combined pivot and anchoring pin for connecting the movable clamping jaw and the attaching sleeve, a lever pivoted to the sleeve and having slotted 60 arms for receiving the lugs of the clamping jaw, and a bail carried by the lever and provided with hooks adapted to engage with the said pivot and anchoring pin.

3. A mop clamp comprising a fixed jaw 65 carried by a tubular sleeve, a handle for the tubular sleeve, a movable resilient jaw pivotally connected to the sleeve, a lever pivotally connected to the sleeve and adapted to engage with the intermediate portion of the 70 resilient jaw, and a fastening member connected with the lever for securing the same in operative position.

4. A mop clamp comprising a fixed jaw and tubular handle attaching sleeve, perforated ears formed at the rear end of the attaching sleeve, a movable jaw of resilient 75 material, pivot means for connecting the rear end of said movable jaw with the perforated ears of the attaching sleeve, a lever pivotally connected to the attaching sleeve, means on said lever engaging the intermediate portion of the movable jaw and means 80 for anchoring said lever to said pivot means.

In testimony whereof I hereunto affix my 85 signature.

SAMUEL ELLIOTT.
